US0D1084765S

(12) **United States Design Patent** (10) **Patent No.:** **US D1,084,765 S**
(45) **Date of Patent:** **** Jul. 22, 2025**

(54) **BEVERAGE CONTAINER**

(71) Applicant: **Pacific Market International, LLC**,
Seattle, WA (US)

(72) Inventors: **Jacob D. Silsby**, Seattle, WA (US);
Andrew C. F. Wahl, Seattle, WA (US)

(73) Assignee: **Pacific Market International, LLC**,
Seattle, WA (US)

(**) Term: **15 Years**

(21) Appl. No.: **29/773,232**

(22) Filed: **Mar. 8, 2021**

Related U.S. Application Data

(62) Division of application No. 29/691,998, filed on May 21, 2019, now Pat. No. Des. 912,466.

CLAIM

The ornamental design for a beverage container as shown and described.

DESCRIPTION

FIG. 1 is a top perspective view of a beverage container showing our new design.

FIG. 2 is a bottom perspective view thereof.

FIG. 3 is a left side elevational view thereof.

FIG. 4 is a front elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines depict portions of the beverage container that form no part of the claimed design.

1 Claim, 7 Drawing Sheets
